B. H. SANDERS.
FLOOR DRAIN.
APPLICATION FILED OCT. 11, 1915.

Patented July 4, 1916.

Fig. 1.

UNITED STATES PATENT OFFICE.

BARNEY H. SANDERS, OF ST. LOUIS, MISSOURI, ASSIGNOR TO AMERICAN FOUNDRY & MFG. CO., OF ST. LOUIS, MISSOURI, A CORPORATION OF MISSOURI.

FLOOR-DRAIN.

1,189,742.

Specification of Letters Patent.

Patented July 4, 1916.

Application filed October 11, 1915. Serial No. 55,285.

To all whom it may concern:

Be it known that I, BARNEY H. SANDERS, a citizen of the United States, residing at St. Louis, Missouri, have invented a certain new and useful Improvement in Floor-Drains, of which the following is a full, clear, and exact description, such as will enable others skilled in the art to which it appertains to make and use the same.

10 This invention relates to floor drains of the type that comprise a shield for preventing the water that enters the joint between the head or top portion of the drain and the surface of the floor in which the drain is set from traveling down the outer side of the drain to the lower end thereof, and thus discoloring the ceiling of the room over which the floor is located or undermining the foundation of the basement floor.

15 One object of my invention is to provide a floor drain of the general type mentioned which is more efficient than the drains of this type now in use, in that the shield or basin which is embedded in the floor to collect the seepage is provided with an integral portion to which the waste pipe or soil pipe is joined, thereby eliminating the possibility of the seepage escaping from the shield into the floor, as is apt to occur when

20 the shield is screwed onto the exterior of the portion of the drain to which the waste pipe is joined.

Another object is to provide a floor drain of the type mentioned, in which the head 35 of the drain can be adjusted vertically with relation to the shield, so as to adapt the drain to floors of various thicknesses and also enable the head of the drain to be arranged flush with the floor line at any time, 40 either when the drain is first set, or after it has been in use for sometime, in case the floor shrinks or becomes lower than the upper edge of the head of the drain.

Another object is to provide a floor drain 45 of the type mentioned, in which the shield or basin is so designed that it will not tend to cause a concrete floor to crack at the point where it contacts with the rim of the shield.

Another object is to provide a floor drain 50 in which the cap is of such a design that it can be adjusted downwardly, so as to close up the joint between the outer surface of same and the floor, in case said joint opens up or becomes abnormally wide, due to 55 shrinkage of the floor away from the head

of the drain. And still another object is to provide a floor drain of the type mentioned, which is so designed that the opening or openings through which the seepage escapes from the shield can be cleaned easily, by 60 simply rotating the adjustable head portion of the drain.

Other objects and desirable features of my invention will be hereinafter pointed out.

Figure 1 of the drawings is a vertical 65 cross-sectional view of a floor drain constructed in accordance with my invention, illustrating the drain arranged in operative position in a floor; and Fig. 2 is a top plan view of the drain.

Referring to the drawings, which illustrate the preferred form of my invention, A designates the head of the drain, and B designates the shield or basin, said shield being embedded in the floor α at a point some distance below the top surface of the floor, as shown in Fig. 1, so as to collect any water that seeps through the joint between the floor and the outer surface of the head of the drain. The head A is arranged centrally 70 with relation to the shield or basin B and is adjustably connected to said shield so that it can be moved vertically with relation to the shield. The head A is substantially funnel-shaped, or, in other words, is provided 75 with a tapered body portion 1 whose upper end merges into a cylindrical-shaped flange 2 and whose lower end merges into a cylindrical sleeve 3. The shield B may be of any preferred shape, but it is provided at its 80 center with a depending tubular-shaped portion 4 into which the sleeve 3 of the head A is screwed, the shield herein shown being provided at its upper edge with a horizontally-disposed flange 5 whose top surface is 85 flat, or substantially flat, so that it will present a relatively wide bearing surface to the material from which the floor is formed, and thus tend to prevent the floor from cracking 90 if it is constructed of concrete. The head 95 A is provided with the usual grill or grating 6 which may be connected to the head in various ways, such, for example, as by means of screws 7 that are screwed into lugs 8 on the inner side of the head A. The sleeve 100 3 on the head A is provided on its exterior with screw threads that coöperate with internal screw threads 4^a on the tubular-shaped portion 4 of the shield, thereby enabling the head to be adjusted vertically 105

110

with relation to the shield, so as to adapt the drain to floors of different thicknesses, or to enable the head to be set flush with the floor line. The water that seeps through the joint 5 between the outer surface of the head A and the floor works downwardly over the outer surface of the head into the shield or basin B and then escapes from said shield into the waste pipe or drain pipe (not shown) which 10 is connected to the tubular-shaped portion 4 on the shield.

In the form of my invention herein shown the tubular-shaped portion 4 is provided at its lower end with an internally screw-threaded portion 4^b to which the drain pipe is connected, but I do not wish it to be understood that my invention is limited to a drain in which the waste pipe, soil pipe or trap is screwed into the portion 4 of the 15 shield, as it is immaterial, so far as my broad idea is concerned, how the shield and waste pipe are connected together. The internally screw-threaded portion 4^a of the part 20 of the shield is provided with one or more vertically-disposed grooves 9 and the sleeve 3 on the head A is provided on its outer surface with one or more vertically-disposed grooves 10, both the grooves being deeper than the screw threads which they intersect. 25

30 The head A is preferably so arranged with relation to the shield B that the coöperating grooves 9 and 10 therein will line up, and thus form passageways through which the seepage can escape from the shield into the drain pipe without liability of leaking into the floor, and thus discoloring the ceiling of the room arranged below the floor or undermining the foundation of the floor, as, for example, in case the drain is set in a basin of 35 the floor. An annular groove 11 that is formed in the inner surface of the tubular-shaped portion 4 of the shield between the internally screw-threaded portions 4^a and 4^b of same provides sufficient space for the 40 seepage to escape from the vertical grooves 9 and 10, even when the head A is adjusted downwardly as far as it will go. In setting the drain it is preferable to fill the shield B with coarse granular material, as shown in 45 Fig. 1, if the floor α is formed of concrete, so as to provide sufficient space for the seepage that collects in the shield.

A floor drain of the construction above described is more efficient than floor drains of 50 this general type that are now in general use, owing to the fact that it is impossible for the seepage to escape from the shield, as the shield is provided with an integral portion in which the waste pipe, soil pipe or 55 trap is joined. As the head of the drain can be adjusted vertically with relation to the shield, the drain can be set in floors of different thicknesses and still maintain the shield at the proper distance below the floor 60 line. And still another advantage of con-

structing the drain in this manner is that the upper edge of the head can always be kept flush with the floor line. The fact that the head A can be adjusted vertically and is provided with a tapered portion makes it 70 possible to screw the head downwardly, and thus seal it firmly against the floor, in case the joint between the outer surface of said tapered portion and the floor opens up, due to shrinkage of the floor. The horizontally-disposed flange 5 on the rim of the shield 75 presents a relatively wide bearing surface for the material in the floor that rests on same, and thus tends to prevent the floor from cracking in case it is formed of concrete. And still another desirable feature of such a drain is that the slots 9 and 10 through which the seepage escapes from the shield can be cleaned easily by simply screwing the head up or down, so as to cause the 80 coöperating screw threads on the exterior of the sleeve 3 and on the interior of the screw-threaded portion 4^a of the shield to pass through said slots, and thus dislodge any material that has collected in same. 85

Having thus described my invention, what I claim, and desire to secure by Letters Patent, is:

1. A floor drain consisting of a shield that is adapted to be embedded in a floor 95 some distance below the top surface thereof, said shield being provided at its center with a screw-threaded opening, a depending tubular-shaped portion on said shield arranged concentric with relation to said opening and adapted to have a drain pipe connected to same, a vertically-adjustable head carried by said shield and provided with an externally-threaded sleeve that fits in the opening at the center of the shield, and means for permitting the seepage that collects in the shield to escape therefrom into the depending tubular-shaped portion on the shield to which the drain pipe is connected. 100

2. A floor drain consisting of a shield provided with an integral portion to which a drain pipe is adapted to be connected, said portion being provided at its upper end with internal screw threads, a head provided with an externally screw-threaded sleeve that is screwed into the internally-screw-threaded portion of said shield, coöperating vertically-disposed grooves on the outer surface of said sleeve and on the interior of the portion to which the sleeve is mounted, and an annular recess formed in the inner surface of the portion of the shield to which the waste pipe is connected at a point below the internal screw threads on 115 said portion. 120

3. A floor drain consisting of a shield having a rim that is provided at its upper edge with an approximately horizontally-disposed flange, an integral depending por- 125 130

tion on said shield to which a waste pipe is adapted to be connected, said portion having two sets of internal screw threads that are arranged on opposite sides of a horizontally-disposed recess formed in the inner surface of said portion, a substantially funnel-shaped head provided at its lower end with an externally screw-threaded sleeve that is screwed into the upper set of screw-
5 threads on the depending portion of the shield, a grill or grating arranged in a flange at the upper end of said head, and co-

operating grooves formed in the outer surface of the sleeve on said head and in the inner surface of the depending portion of 15 the shield that surrounds said sleeve.

In testimony whereof I hereunto affix my signature in the presence of two witnesses, this seventh day of October 1915.

BARNEY H. SANDERS.
